UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

SEAM FOR SEWED ARTICLES.

1,293,576.

Specification of Letters Patent.

Patented Feb. 4, 1919.

Application filed December 24, 1915. Serial No. 68,518.

To all whom it may concern:

Be it known that I, SAMUEL GEORGE TATE, a citizen of the United States, residing at Chicago, in the county of Cook, State of Illinois, have invented certain new and useful Improvements in Seams for Sewed Articles, of which the following is a description, reference being had to the accompanying drawing and to the figures of reference marked thereon.

The invention relates to new and useful improvements in seams for sewed articles, more particularly to a seam which may be used for ornamental purposes, for joining the edges of fabric sections, or for forming an edging along the edge of a fabric.

An object of the invention is to provide a seam having a plurality of needle threads formed into a series of parallel rows of needle thread loops wherein certain of the needle threads on the upper face of the fabric between adjacent loops of certain rows are extended laterally and disposed in overlapped relation and concatenated with other needle threads, and wherein a single thread concatenates with all the needle thread loops on the under face of the fabric, whereby a relatively wide flat seam is produced in which the connecting threads on the upper face of the fabric are formed from the needle threads and in which the connecting threads on the under face of the fabric are formed from a single looper thread.

In its broadest aspect, the invention consists in concatenation and arrangement of threads with respect to a fabric generally under which is included the use of the seam applied for ornamental purposes only on the flat face of a fabric or at the edge of a fabric where the seam may also form the purpose of an artificial selvage. In a more restricted and very important aspect, the invention includes the same concatenation and arrangement when applied to two fabrics or fabric sections whose edges are slightly overlapped or abutted without overlapping, in which event certain of the stitches or loops are anchored in respect to the fabric sections and the raw edges of the fabric sections are covered by certain of the threads.

In the drawings:

Figure 1 is a plan view showing, more or less diagrammatically and on an enlarged

scale, my improved seam joining abutting edges of fabric sections;

55

Fig. 2 is a bottom plan view of the same; Fig. 3 is a transverse sectional view of the seam shown in Fig. 1;

Fig. 4 is a view, similar to Fig. 3, but showing the edges of the fabric sections 60 overlapped and penetrated by the needle thread loops of the inner rows of needle thread loops;

Fig. 5 is a view, similar to Fig. 3, but showing the threads utilized for forming an 65 edging on a fabric; and

Fig. 6 is a similar view, but showing the threads utilized for forming an ornamentation on the body of the fabric.

In Figs. 1 to 3, inclusive, of the drawings, 70 I have shown my improved seam as used for joining abutting edges of fabric sections *a* and *b*, said sections being abutted at *c*. As shown in the drawings, the seam is composed of four needle threads and one 75 looper thread. The needle thread 1 is formed into a series of loops 2. These loops are passed through the fabric section *a* to the under face thereof. The needle thread 3 is formed into a series of loops 4, and these loops are 80 passed through the fabric section *b*. The needle thread 5 is formed into a series of needle thread loops 6 which are passed through the fabric section *a* in a line between the meeting edges of the fabric sections and the row of needle thread loops 85 formed by the needle thread 2. The needle thread 7 is formed into a series of loops 8 which are passed through the fabric section *b* in a line substantially the same distance 90 from the meeting edges *c* as are the needle thread loops formed by the needle thread 2.

On the upper face of the fabric, the needle thread 1 between adjacent needle thread loops extends laterally and passes around 95 the respective loops formed by the needle thread 3. In other words, the loops formed in the needle thread 3 in the construction of the seam pass down through these laterally extending loops formed by the needle 100 thread 1. The needle thread 7 between adjacent needle thread loops extends laterally in an opposite direction from the laterally extending portions of the needle thread 1, and these laterally extending portions of the 105 needle thread 7 pass around the respective

needle thread loops formed by the needle thread 5. In other words, the loops formed by the needle thread 5 pass down through the laterally extending portions formed by 5 the needle thread 7.

The opposed needle thread loops of the needle threads 3 and 5 are disposed in a line which passes substantially midway between lines passing through adjacent pairs of opposed needle thread loops in the needle threads 1 and 7. The laterally extending portions of the needle threads 1 and 7, therefore, are directly opposed to each other and one overlaps the other. The needle threads 3 10 and 5 cross over the strands of the laterally extending portions of the needle threads 1 and 7 and tie the same down.

On the under face of the fabric sections, there is a single looper thread 8. As viewed 20 in Fig. 2, the direction of the feed is indicated by the arrow. The looper thread passes from the left to the right through the needle loops, indicated at *x*. The looper is, of course, curved so that the needles may be 25 set for forming simultaneously the needle loops positioned as above described and, at the same time, said looper will co-operate one after another with said needles. The end of each looper thread loop, indicated at 9, will 30 be locked by the next needle loop 8. One strand of the looper thread extends longitudinally of the seam, as at 10, so as to be entered by the next needle thread loop 4. The looper thread is also extended, as at 11, 35 so as to be entered by the next needle loop 6 and the same strand of the looper thread is likewise extended, as at 12, to enter the next needle loop 2.

From the above description, it will be 40 apparent that I have provided a single thread beneath the fabric which forms cross threads extending transversely of the seam, and cross threads extending more or less longitudinally of the seam. This looper thread 45 concatenates with all the needle thread loops, and the cross threads above referred to, not only tie together the sections of the fabric, but effectively cover the loose ends of the threads at the abutted edges of the fabric 50 sections. On the upper face of the fabric, I have interconnected the rows of needle thread loops by the laterally extending portions of the needle threads so that I produce a seam having a plurality of rows of needle 55 thread loops which are interconnected on the upper face of the fabric without using any extra cross thread. The needle thread loops formed by the needle threads 1 and 7 serve as anchoring loops for making a strong and 60 durable connection for the fabric sections. The laterally extending portions of the needle threads not only connect the fabric sections, but also effectively cover the loose ends of the threads at the abutting edges of 65 the fabric sections. The overlapping of

these laterally extending portions formed in the needle threads 1 and 7, and the tying down thereof by the needle threads of the inner rows of connected loops, greatly increases the effectiveness of the covering of 70 the abutting edges.

In practice, my improved seam will be made by four needles set in an arc extending transversely of the line of feed, the center pair of needles being disposed in a plane in 75 rear of the front pair of needles. The looper will move in an arc corresponding to the arc of the needles and, as above noted, will co-operate with all four needles. It will be understood, however, that from certain aspects of the invention two loopers might be used, one looper co-operating with the outer pair of needles and the other with the inner pair of needles.

In Fig. 4 of the drawings, I have shown 85 my improved arrangement of threads as used for uniting fabric sections wherein the edges of the fabric sections are overlapped, as at *d*, instead of being abutted. The sections are sufficiently overlapped so that the 90 inner rows of the needle thread loops penetrate both fabric sections. This greatly strengthens the seam uniting the fabric sections.

In Fig. 5 of the drawings, I have shown 95 my improved arrangement of threads as utilized for forming an edging on a fabric. The loops of the outer row of needle thread loops 7 pass over the edge of the fabric and not through the fabric. The loops of the 100 other rows of needle thread loops enter the fabric, and the connecting threads, above described, effectively cover and tie down all the loose cut ends of the threads forming the fabric.

In Fig. 6 of the drawings, I have shown 105 my improved arrangement of threads as used for forming an ornamental seam. In this instance, the needle thread loops pass through the body of a single fabric section. 110 The threads are laid and concatenated precisely in the manner described in connection with Figs. 1 to 3, inclusive, of the drawings. The connected threads on the upper face of 115 the fabric produce an ornamental effect.

It is obvious that minor changes in the details of construction and the arrangement of the threads may be made without departing from the spirit of the invention, as set forth in the appended claims.

Having thus described the invention, what is claimed as new is:—

1. In a seam, the combination with a fabric, of a plurality of spaced rows of needle thread loops projecting through the 125 fabric, and a single looper thread concatenating with all the needle thread loops beneath the fabric, the needle threads on the surface of the fabric entered by the needle and between adjacent loops of the outer rows 130

- respectively extending laterally in opposite directions and disposed in overlapping relation and concatenating with the loops of an intermediate row of needle thread loops.
- 5 2. In a seam, the combination with a fabric, of four spaced rows of needle thread loops projecting through the fabric, and a single looper thread concatenating with all the needle thread loops beneath the fabric, the needle threads between adjacent loops in the outer rows respectively extending laterally in opposite directions and disposed in overlapping relation and concatenating respectively with the loops of the inner row of needle thread loops farthest therefrom.
- 10 3. In a seam, the combination with a fabric, of four spaced rows of needle thread loops projecting through the fabric, and a single looper thread concatenating with all the needle thread loops beneath the fabric, the needle threads between adjacent loops in the outer rows respectively extending laterally in opposite directions and disposed
- 15 20 25 30 35 40 45 50 55 60 65 70 75 80 85 90 95 100 105
- in overlapping relation and concatenating respectively with the loops of the inner row of needle thread loops farthest therefrom, the needle threads forming the inner rows of needle thread loops overlying and tying down the laterally extending portions of the needle threads, forming the outer rows of needle thread loops.
4. In a seam, the combination with abutted fabric sections, of four spaced rows of needle thread loops projecting through the fabric, the opposite needle thread loops of the outer rows being respectively disposed in lines lying between adjacent lines passing through the opposed needle thread loops of the inner rows, and a single looper thread concatenating with all the needle thread loops beneath the fabric, the needle threads between adjacent loops of the outer rows respectively extending laterally across the juncture of the fabric sections in opposite directions and disposed in overlapping relation and concatenating with the loops of the inner row of needle thread loops farthest therefrom.
5. In a seam, the combination with abutted fabric sections, of four spaced rows of needle thread loops projecting through the fabric, the opposite needle thread loops of the outer rows being respectively disposed in lines lying between adjacent lines passing through the opposed needle thread loops of the inner rows, and a single looper thread concatenat-

ing with all the needle thread loops beneath the fabric, the needle threads between adjacent loops of the outer rows respectively extending laterally across the juncture of the fabric sections in opposite directions and disposed in overlapping relation and concatenating with the loops of the inner row of needle thread loops farthest therefrom, the needle threads forming the inner rows of needle thread loops overlying and tying down the laterally extended portions of the needle threads forming the outer rows of needle thread loops.

6. In a seam, the combination of fabric sections, stitches for joining and covering the edges of the fabric sections, said stitches comprising four parallel rows of needle thread loops projecting through the fabric sections, the opposed needle loops in the outer rows lying in lines located between lines passing through opposed needle loops in the inner rows, and a single looper thread concatenating with all of the needle loops beneath the fabric sections, the respective needle threads between adjacent loops in the outer rows extending laterally across the juncture of the fabric sections and in opposite directions and disposed in overlapping relation and concatenating respectively with the loops of the inner row of needle thread loops farthest therefrom, the needle threads forming the inner row of needle thread loops overlying and tying down said laterally extending portions of the needle threads forming the outer row of needle thread loops.

7. In a seam, the combination with a fabric, of four rows of needle thread loops projecting through the fabric, and means for interlocking the needle thread loops beneath the fabric, the needle threads between adjacent needle thread loops in the outer rows respectively extending in opposite directions and disposed in overlapping relation and concatenating respectively with the needle thread loops in the inner row farthest therefrom, both the needle threads forming the inner rows of needle thread loops overlying and tying down said laterally extending portions of the needle threads forming the outer rows.

In testimony whereof, I affix my signature in the presence of two witnesses.
